UNITED STATES PATENT OFFICE.

FRANK G. HEWLETT, OF BELLAMY, ALABAMA, ASSIGNOR TO ALLISON LUMBER COMPANY, INC., OF BELLAMY, ALABAMA, A CORPORATION.

CHOCK BLOCK.

Application filed May 12, 1924. Serial No. 712,878.

To all whom it may concern:

Be it known that I, FRANK G. HEWLETT, a citizen of the United States, residing at Bellamy, in the county of Sumter and State of Alabama, have invented certain new and useful Improvements in Chock Blocks, of which the following is a specification.

This invention relates to a chock block, and particularly to a construction adapted to retain in position a vehicle during transportation or when in storage, by engagement with a wheel thereof.

Chocks of this character are very generally formed from a solid block of wood for the purposes of stability and economy, with the grain of the wood extending longitudinally of the block. Such a block when under strain or pressure is liable to split on the line of the grain, particularly at the upper portion which is not supported by the fastening devices, and it is therefore important to retain the maximum of material at this portion of the block while providing at its base a heel or flange to facilitate the introduction of nails or securing means which are preferably passed through apertures previously formed in the block. It is also highly desirable that the face of the block at the apertures be formed to permit complete driving of the nails or securing means and prevent contact of the driving tool with the face of the block. For this purpose it has also been found important to groove the opposite sides of the block and thereby form flanges having diverging faces one of which is adapted to receive the fastening devices while the other permits the direct application of a tool in the driving of such devices.

The invention comprises a novel and improved construction of wooden block having a wheel engaging face and an oppositely inclined outer face disposed in a single plane and formed with a recessed portion having walls at a right angle to each other and jointed at their angle by a curved face provided for the introduction of a fastening device.

A further object of the invention is to provide a novel and improved construction of chock block adapted to be formed from a single piece of material and provided at its opposite side faces with grooves forming flanges having an inclined face provided with apertures to receive fastening devices

for the purpose of securing the block in position.

Other and further objects and advantages of the invention will be hereinafter set forth and the novel features thereof defined by the appended claim.

In the drawing:

Figure 1 is a perspective of one form of the invention;

Figure 2 is a rear elevation of a modified form of the block;

Figure 3 is a side elevation of the same;

Figure 4 is a rear elevation of a further modification of the invention; and

Figure 5 is a side elevation thereof.

Like reference characters refer to like parts throughout the several figures of the drawing.

In the use of chock blocks for shipping purposes the blocks are seldom returned to the shipper and an important element in their construction, therefore, is the economy in material used and in the production of the block for that purpose the blocks are usually formed of wood in a single piece and it is desirable to form the opposite faces thereof at such relative angles that a series of the blocks may be cut from a single piece of material in the most economical manner, while in the finishing of the block it is essential to maintain sufficient material at the upper portion thereof to effectually support the strain applied thereto in use.

In the form of the invention shown in Figure 1 the block 10 is provided with a curved front face 11 adapted to engage the periphery of a wheel or vehicle tire and for that purpose may also be formed concave as indicated at 12, this face being extended from the upper to the lower surfaces of the block so as to fit snugly beneath the wheel. The rear face 13 of the block is inclined at an angle opposite to the front face and preferably such angle is acute to the plane of the base 14. Such a construction provides a body of material at the upper portion 15 of the block sufficient to provide the proper strength of material at this portion. For the purpose of providing a heel 16 to receive the securing means for the block the rear face thereof immediately above the heel is formed with a vertical wall 17 while the face 18 of the heel is disposed at a right angle thereto and these walls joined by a curved portion 19 at which point the

apertures 20 are provided to receive the nails or other attaching devices and extend inwardly and downwardly through the block.

- 5 This construction provides a proper surface by which the head of the securing device may be driven flush with the block and space provided for the proper manipulation of the driving tool for that purpose. Such
10 an arrangement avoids the difficulty of driving a headed fastener into a sharp angle portion of the block as in such case the head is liable to be driven into the wood of adjacent surfaces and the tool brought
15 into violent contact with the block, resulting in damage thereto and possible splitting of the block. The opposite side walls of the block are provided with apertures 21 extending inwardly and downwardly and
20 adapted to receive attaching devices at such points.

In the modified form of the invention shown in Figures 2 and 3, the front and rear faces of the block are formed as before described and the opposite side faces are provided with grooves 22 having angularly disposed diverging walls, the wall 23 thereof being inclined outwardly, and extending inwardly and downwardly therefrom the aperture 24 is provided to receive the attaching device. This arrangement of said grooves provides an open space for the reception of the driving tool and a plane surface to permit the complete securing
35 movement of the nail or other device.

In the form of the invention shown in Figures 4 and 5 the outer face 25 is curved or inclined and the rear face 26 formed substantially straight, so that with the top 27 and the base 28 a structure having three rectangular walls is provided. In this form of the invention the attaching heel is omitted and the base 28 may be extended to provide sufficient area for additional attaching devices. Each side of the block is

formed with grooves 29 similar to those described in connection with Figures 2 and 3 and the apertures 30 for the attaching nails extend inward and downward from the lower face of the groove 29.

The construction and operation of this chock block will be apparent from the foregoing description from which it will be seen that the same may be most economically formed from the same piece of material and is adapted to retain a sufficient body at its upper portion to resist the downward strain thereon and prevent splitting of the block along the longitudinal grain thereof while the disposition of the attaching apertures is so regulated as to permit the nails or other devices to be completely set in position and sufficient space provided for the operation of a driving tool and prevent its contact with the surface of the block. The provision of the said grooves affords additional securing surface without affecting the strength of the block and permits the direct application of the attaching devices through the flanges formed by the angle grooves which may be formed by a single operation upon a proper machine.

Having thus described my invention, what I claim as new and desire to secure by Letters Patent is:

A chock comprising a wooden block having a wheel engaging face and oppositely inclined rear faces disposed in a single plane and formed with an intermediate recessed portion having walls at a right angle to each other and joined at their angle by a curved face provided for the introduction of a fastening device, and grooves at the opposite side faces of said block forming flanges having an inclined face provided with an aperture to receive a fastening device.

In testimony whereof I affix my signature.

FRANK G. HEWLETT.
